(57) **CLAIM**

The ornamental design for a drinking cup packaging for golf balls, as shown and described.

DESCRIPTION

FIG. 1 is a perspective view of drinking cup packaging for golf balls showing our new design;

FIG. 2 is a front elevation view thereof;

FIG. 3 is a first side elevation view thereof;

FIG. 4 is a rear elevation view thereof;

FIG. 5 is the other side elevation view thereof;

FIG. 6 is a top plan view thereof; and,

FIG. 7 is a bottom plan view thereof.

The parts shown in broken lines in FIGS. 1–7 are shown for illustrative purposes only and forms no part of the claimed design.
